UNITED STATES PATENT OFFICE.

FREDERICK MACKINTOSH, OF SCHENECTADY, NEW YORK, ASSIGNOR TO
GENERAL ELECTRIC COMPANY, A CORPORATION OF NEW YORK.

RHEOSTAT.

SPECIFICATION forming part of Letters Patent No. 714,927, dated December 2, 1902.

Application filed May 31, 1901. Serial No. 62,634. (No model.)

To all whom it may concern:

Be it known that I, FREDERICK MACKINTOSH, a citizen of the United States, residing at Schenectady, county of Schenectady, State of New York, have invented certain new and useful Improvements in Rheostats, of which the following is a specification.

This invention relates to electric rheostats, the object being to provide an instrument of this character of very compact construction and cheap to manufacture and low heating. In carrying out the invention I form the resistance units of the rheostat of punched-metal grids, which are coated with insulating heat-refractory enamel, except at the ends, where the connections are made, and I clamp a plurality of these grids together with intervening metal radiating-plates. The grids are mounted on rods secured in a supporting-frame, and the radiating-plates are kept in place by interlocking projections between the grids and the plates. Taps are taken from the ends of certain grids and led to contact-studs mounted on a switch-plate, by which the amount of the resistance is varied.

The invention involves various features of novelty, which will be hereinafter pointed out in the claims.

In the accompanying drawings, which illustrate the invention, Figure 1 is a side elevation, partly in section, of a rheostat embodying my improvements. Fig. 2 is a bottom plan view, partly in section; and Fig. 3 is a sectional detail showing the plan of interlocking the grids and radiating-plates.

1 1^a 1^b 1^c represent the feet of a supporting-frame, upon which the grids of the rheostat are mounted. This is connected to a slate or marble top plate 2, in which are mounted contact-studs, as indicated in Fig. 1, from which lead conductors 3 3^a, &c., to different sections of the group of grids. Over the contacts sweeps a brush 4, as usual, to vary the amount of resistance in the circuit. The resistance-grids are formed of punchings, as 5, from sheet metal, provided with supporting-arms 5^a 5^b, adapted to be slid over a bar or rod 6, covered with insulating material. The

grids are enameled, except at the ends 5^a 5^b, which latter are not coated. After being punched or during the punching operation longitudinal ribs are struck up at one or more points in the grids, as indicated at 7 7^a, adapted to aline with corresponding depressions in metal radiating-plates 8, which are placed between the several grids. The desired number of the grids and plates are assembled, as indicated in Fig. 2, and clamped together by bars 9 9^a, which are also mounted on the supporting-rods 6 6^a. The several grids are alternately connected at the ends, so as to form an uninterrupted circuit from end to end of the grids, insulated washers 10 11 being inserted between alternate pairs of grids at the two ends. Connector-clips 12 are secured to the grids at intervals at one end, to which may be connected the leads 3 3^a, connecting with the several contact-studs. The alternate joints at one side of the group of grids may be electrically connected by the connectors 7^a 12, and at the other end metal washers 13 may be used. The other joints are insulated by mica washers 10 11. The grids and intervening washers are assembled on insulating-bushings, as 14, around the rods 6 6^a, the clamp-bars 9 and 9^a put in place, and the radiating-plates 8 inserted, so as to bring the projections in alinement. The clamp-nuts 15 15^a are then tightened, thus binding the several grids into close engagement with the radiating-plates and holding all parts solidly together. The rods may then be locked in place on the supporting-legs of the rheostats by clamp-nuts, as indicated in Fig. 2. Circuit connections with the terminals may be made, as usual. When the switch 4 is moved over the contact-studs, a greater or smaller number of the grids is cut into circuit.

The enamel on the grids prevents short-circuiting, and yet promotes good heat-dissipating contact with the intervening metal plates, while the contact-faces of alternate grids on the supporting-rods are held in close engagement by the nuts 15 15^a, thereby insuring good contact. The heat-radiating plates are prevented from falling out by the

interlocking devices described and are held in good heat-conductive relation to the grids without interfering with the insulation.

What I claim as new, and desire to secure by Letters Patent of the United States, is—

1. A rheostat composed of a plurality of resistance-grids, each coated with a thin adherent layer of insulating-enamel assembled and clamped together with intervening heat-radiating plates.

2. A rheostat comprising a plurality of resistance-grids enameled with a refractory material except at the ends and held in contact with heat-radiating plates, and means for clamping the several grids together at the ends to connect them in series.

3. A rheostat comprising a plurality of grids covered with a thin insulating-enamel and held in contact with intervening heat-radiating plates, interlocking projections being provided on the grids and plates, to prevent relative movement.

4. A rheostat comprising a plurality of resistance-grids formed of sheet-metal stampings each covered with a thin adherent insulating-enamel and connected in series, heat-radiating plates between the several pairs of grids insulated therefrom, and interlocking connections for preventing relative displacement.

5. A rheostat comprising a plurality of resistance-grids connected in series, each covered with a thin adherent insulating-enamel, heat-radiating plates between the several pairs of grids insulated therefrom, and interlocking tongue-and-groove connections for preventing relative displacement.

6. A rheostat comprising a plurality of resistance-grids each covered with a thin adher-

ent insulating-enamel connected in series relation, intervening heat-radiating plates interlocking with the grids, and means for clamping them in firm engagement.

7. A grid for an electric rheostat having bare contact-sfaces at its ends, and a coating of enamel on the body of the grid to serve as an insulating-spacer.

8. A rheostat provided with a plurality of resistance-grids each coated with a thin adherent insulating-enamel mounted on supports at their ends and insulated therefrom, insulating-washers between the several pairs of grids, insulated heat-radiating plates between the several grids held in close contact therewith, and means for clamping the several parts in firm engagement.

9. A rheostat comprising a plurality of enameled resistance-grids, insulated supporting-rods therefor, said grids being connected in series relation, metal plates between the grids mechanically interlocked therewith, clamping devices for holding the grids and plates under pressure, and connections with contact-studs from different parts of the grid series.

10. A rheostat comprising a plurality of resistance-grids, insulated heat-radiating plates mechanically interlocking therewith, supporting-rods threading perforations in the ends of the grids, and clamping devices for holding the parts in firm engagement.

In witness whereof I have hereunto set my hand this 27th day of May, 1901.

FREDERICK MACKINTOSH.
